UNITED STATES PATENT OFFICE.

ALLEN G. URBAHNS, OF VALPARAISO, INDIANA, ASSIGNOR TO MCGILL MANUFACTURING COMPANY, OF VALPARAISO, INDIANA, A CORPORATION OF INDIANA.

LAMP GUARD.

Application filed September 12, 1925. Serial No. 56,013.

My invention relates to lamp guards and more particularly to a quick detachable wire lamp guard for application to lamp sockets.

The purpose of my invention is to provide 5 a lamp guard that can be quickly attached and removed without the use of any tools and which will grip firmly when in position. As is well known, all sockets have some form of bead thereon such as a screw thread for 10 securing shade holders of similar devices thereto. My invention contemplates the provision of means frictionally engaging the outer face of the socket inwardly beyond said bead so as to hold the lamp guard firmly 15 in position under ordinary circumstances, but permitting the removal of the same by an outward pull on the same without the use of tools.

More particularly it is a purpose of my invention 20 to provide a lamp guard provided with a body portion having yielding fingers extending endwise beyond the same that engage with the outer surface of the lamp socket inwardly of the above mentioned bead 25 to firmly hold the lamp guard in position.

Lamp guards of this character are usually 30 made of wire and the wire has a certain amount of resiliency sufficient to hold the guard in place frictionally and accordingly 35 the resilient fingers are preferably extensions of certain of the wires of the lamp guard and preferably are held from outward movement beyond a certain limit by means of a stiffening ring or a confining member spaced a 40 short distance from the free ends of the wires. The wires preferably incline slightly inwardly beyond said stiffening ring and are provided with recurved ends which act as cam members when the guard is moved axially 45 into engagement with the socket to force the free ends of the wires or other resilient members outwardly to pass over the bead on the socket after which the same firmly engage with the socket inwardly of said bead to hold the same in place.

While the lamp guard is preferably made 50 with an open enlarged end for ready insertion and removal of the lamps from the socket, yet, if desired, the end may be made closed as this is immaterial, as far as the principle 55 that is involved, for holding the lamp guard in position on the socket.

Other objects and advantages of the invention will appear as the description of the 55 accompanying drawings proceeds. How-

ever, I desire to have it distinctly understood that I do not intend to limit myself to the exact details shown or described, but that I intend to include as part of my invention all such obvious changes and modifications of parts as would occur to a person skilled in this art and as would fall within the scope of the claims.

In the drawings:

Fig. 1 is a side elevation of my improved 65 lamp guard showing the same applied to a lamp socket.

Fig. 2 is a section taken on the line 2—2 of Fig. 1, the interior mechanism of the lamp socket being omitted as the particular construction thereof has no bearing on the invention.

Referring in detail to the drawings, my improved lamp guard comprises a plurality of longitudinally extending wires 5 which 75 are secured together by means of pairs of spacing rings 6 and 7, 8 and 9. The rings 6 and 8 are arranged externally of the wires 5, and the rings 7 and 9 internally thereof to firmly brace the same, the wires 5 being offset at 10 to accommodate the ring 9 and being provided with loops 11 at the ends thereof embracing the wires 7. Said wires 5, 6, 7, 8, and 9 are firmly secured together in any suitable manner at their engaging portions. 85 This is usually done in the tinning operation, the tin soldering the parts together. The hoops or ring like wire members 6 and 7 are larger than the members 8 and 9 so that the wires 5 flare outwardly at the portions 12 90 thereof. The longitudinal portions 13 of the wires incline at a greater angle than the portions 12 and are provided with offsets 14 spaced a short distance from the ends thereof to receive the stiffening ring 95 15 which is flat and which has the greatest dimension thereof arranged diametrically as will be clear from Figs. 1 and 2. The ring 15 is notched as is indicated at 16 to receive the offset portions 14 of the wires 100 5 thus holding the wires 5 properly spaced and preventing the outward movement thereof due to the confining action of the ring or hoop 15. Said wires may merely lie in the notches 16 or may be secured in the 105 notches by means of the tin in the tinning operation as described above.

The free ends 17 of the wires 5 are inclined inwardly beyond the ring 15 and are provided with substantially parallel portions 110

18 that lie parallel to the axis of the guard beyond the portions 17 and with the recurved hook-like members 19 that turn outwardly as will be clear from Fig. 1.

5 The guard is applied to a lamp socket, such as the socket 20 shown in Fig. 1, which is provided with some form of bead at 21 and with a substantially cylindrical portion 22 inwardly beyond the bead. The bead 21 10 is ordinarily in the form of a screw thread, although any form of enlargement would serve the same purpose.

In order to place the lamp guard in position on the socket 20, the same is moved axially into engagement with the socket, the recurved ends 19 acting as cam members to force the free ends of the wires 5 outwardly away from each other so as to pass over the bead 21, the ends of the wires being, of course, 20 spaced more closely together than the diameter of the portion 22 of the socket. Accordingly, the portions 18 thereof will be held in frictional engagement with the socket portion 22 due to the normal tendency of the wires, 25 which have a certain amount of resiliency to move inwardly toward each other. The guard is removed by an outward pull on the same. This outward pull requires a considerable amount of force due to the fact 30 that a very large number of resilient gripping fingers are in engagement with the socket at closely spaced intervals and due to the fact that the enlargement 21 lies outwardly beyond the portion with which the 35 portions 18 of the wires 5 are in engagement.

If any difficulty is experienced in removing the guard by a straight pull, a sidewise twist at the same time that the pulling is done, will readily remove the guard. The construction of the device is, however, such that 40 the guard will not accidentally come off the socket. Moreover, due to the construction thereof, the lamp guard is very easily placed in position and easily removed without the use of any tools or the fastening or unfastening of any catches.

Having thus described my invention what I desire to claim and secure by United States Letters Patent is:

1. In a lamp guard, a body portion having a plurality of resilient fingers projecting endwise therebeyond, and a ringlike stiffening member for said fingers limiting the outward movement of said fingers, said ringlike member having a greater radial 55 width than thickness to make the same unyielding.

2. In a lamp guard, a body portion having a plurality of resilient fingers projecting endwise therebeyond, and a ringlike stiffening member for said fingers limiting the outward movement of said fingers, said ringlike member having a greater radial width than thickness to make the same unyielding and having an annular series of wire receiving notches at the inner edge thereof.

In witness whereof, I hereunto subscribe my name this 31st day of August, A. D. 1925.

ALLEN G. URBAHNS.
